UNITED STATES PATENT OFFICE.

JAMES G. HENDRICKSON, OF BAYONNE, NEW JERSEY, AND ERNEST J. ALLEN, OF ROCKVILLE CENTER, NEW YORK, ASSIGNORS, BY MESNE ASSIGNMENTS, TO NEW YORK LABELLING MACHINE COMPANY, A CORPORATION OF NEW YORK.

LABELING-MACHINE.

SPECIFICATION forming part of Letters Patent No. 765,971, dated July 26, 1904.

Application filed June 5, 1902. Serial No. 110,259. (No model.)

To all whom it may concern:

Be it known that we, JAMES G. HENDRICKSON, of Bayonne, in the county of Hudson and State of New Jersey, and ERNEST J. ALLEN, of Rockville Center, in the county of Nassau and State of New York, citizens of the United States, have invented certain new and useful Improvements in Labeling-Machines, of which the following is a specification, taken in connection with the accompanying drawings, which form a part of the same.

This invention relates to labeling-machines, and relates more particularly to machines for applying a label to three sides of an article. In the accompanying drawings, in which the same reference character indicates similar parts in the several figures, Figure 1 is a side elevation of a machine embodying this invention, parts being broken away. Fig. 2 is a detail. Fig. 3 is a plan view. Fig. 4 is a sectional plan view taken substantially on the line 4-4 of Fig. 1. Fig. 5 is a detail elevation of the label-box. Fig. 6 is a plan view of the same. Fig. 7 is a detail.

The frame A, which is indicated in Fig. 1, is composed of two similar side members rigidly secured together by suitable supports. The label-box E is mounted in the frame, this box being supported by the two vertical rods E², which are mounted upon the supports E³. The label-box by suitable means may be adjusted at any desired height upon these rods, so as to coöperate properly with the articles to which the labels are applied. As indicated in detail in Figs. 5 and 6, the label-box is provided at its rear end with the label-platen F⁵, which is secured to the platen-stem F' so as to move horizontally. This platen-stem has upon its under surface the rack F², which engages the teeth of the pinion F⁴, mounted in the bracket F, secured to the label-box by the member F³. The pinion F⁴ is operated by the spiral spring, (indicated in dotted lines,) so that this pinion normally tends to press the label-

45 platen outward and in this manner forces the stack of vertically-disposed labels toward the outer end of the label-box.

The platen-latch E¹¹ is pivoted upon the support F and is held down by the strong spring E¹², so that it normally engages the upper side 50 of the platen-stem. This grips the platen-stem sufficiently, so that the platen is prevented from moving outward under the action of the spring-operated pinion F⁴. This latch is, however, released from engagement with 55 the platen-stem whenever the stop E⁸ on the grip-lever E¹⁴ comes into engagement with the screw E¹³ on the latch.

The grips E' are mounted on either side of the label-box and, as is indicated in Fig. 4, extend around the forward end of the same, so that they engage the first label in the stack F⁶. These grips are guided by the bars E¹⁶ on either side of the label-box and are connected by the rods indicated to the links E¹⁵. 65 The grip-rods E⁵ pass through suitable bearings indicated on the sides of the label-box, and their rear ends are engaged by the springs E⁶, which normally force them backward to cause the grips to engage the labels. These 70 grip-rods are secured to the bar E⁴, which is operated by the grip-lever E¹⁴, pivoted to the bracket F. This bell-crank grip-lever E¹⁴ has its end connected to the bar E⁴ by the link E⁷. The roll E⁹, which is operated by the cam E¹⁰ 75 on the power-shaft D⁴, is adjustably mounted in a slot in the grip-lever, so that it coöperates properly with this cam at all times and allows in this manner the vertical adjustment of the label-box. The operation of the label-box is as follows: The stack of vertically-disposed labels is held in the label-box by the grips E', which are spring-pressed. The outer label has paste applied to it, and when an article is pressed against this label the grips 85 are released to allow the label to be withdrawn edgewise. The grips are moved outward to release this label by the grip-lever which has been described, which is operated by the cam E¹⁰ to move the grips into the released position. (Indicated in Fig. 5.) When the grips are released, the platen-latch is forced into engagement with the platen-stem and prevents the platen from pushing the stack of labels

outward against the grips. After the pasted label has been withdrawn from the label-box the cam E^{10} ceases to operate upon the grip-lever and the springs E^6 move the grips so that they again engage the stack of labels, and at this time the stop E^8 engages the screw E^{12} and withdraws the platen-latch from the platen-stem, so that the pressure of the spring once more operates upon the platen to feed the stack of labels forward against the grips.

The paste apparatus comprises the paste-reservoir A^2 , which is secured to the frame by the nuts A^3 . The feed-roll A' is mounted in this reservoir and is revolved continuously during the operation of the machine by the beveled gears $A^4 A^5$, the shaft A^{12} of the gear A^5 being driven from the power-shaft D^4 by the belt A^{13} . (Indicated in Fig. 4.) In this manner the feed-roll is continuously operated and supplies paste to the paste-roll A^6 whenever this roll is in contact therewith. The paste-roll is revolvably mounted in the paste-slide A^7 , which reciprocates upon the traverse-rods A^8 . These traverse-rods are mounted at either end in the heads A^{17} , and these heads are mounted upon the tilting-shaft A^{10} , having suitable bearings in the frame of the machine at either end of the traverse-rods. This tilting-shaft is operated to tilt the paste-roll from the position indicated in Fig. 1 to the dotted position indicated in that figure, so that it may be traversed across the label-box to apply paste to the outer label in the stack. The cam A^{16} on the power-shaft D^4 engages the roll A^{18} on the tilting-lever A^{15} . (Shown in detail in Fig. 7.) This lever, through the link A^{19} , moves the tilting-shaft by the crank A^{11} , secured to this shaft, so that by this means the paste-roll is tilted from a horizontal to a vertical position. The paste-roll is traversed moving along the traverse-rods A^8 by the traverse-arm C , pivoted to the frame of the machine at C^5 and having its forward end formed to engage the traverse-lug extending around the paste-slide A^7 , as indicated in Fig. 1. The traverse-arm is driven from the power-shaft D^4 in the following manner: The mutilated gear C^4 is mounted on this power-shaft, and during a half-revolution the pinion C^3 is given a complete rotation, so that the crank C^2 , secured to this pinion, is rotated. The link C' serves to connect this crank with the traverse-arm C , so that at every revolution of the power-shaft the traverse-arm is given a quick oscillation, so as to carry the paste-roll across the label-box in contact with the forward label in the box. The roller A^9 on the paste-slide comes into contact with the guide A^{11} under these conditions to maintain the paste-roll in contact with the labels.

The carrier mechanism for moving the articles to be labeled through this machine comprises in general terms the following elements: The reciprocating plunger B engages an article placed against the stop B^5 and forces

this article into the elevator D^7 and into contact with the forward pasted label in the stack. The elevator then moves upward, the grips having released the forward label, which is carried upward with the article adhering to it. Then when the elevator reaches the upper level the ram G^{11} moves forward, carrying the article out of the elevator and between the two wipers and into contact with the cushion H' . (Indicated in Fig. 3.) This cushion moves forward, and the projecting ends of the label are smoothly applied to the sides of the article by the pivoted wipers H . The ram having retreated, the completely-labeled article is engaged by the ejector D^9 and moved laterally out of the path of the cushion, whereupon the cushion moves back into its forward position. (Indicated in Fig. 3.) As is indicated in Fig. 4, the article shown adjacent the plunger B in dotted lines is of such size that the labels in the stack F^6 extend completely across the face of the article and are also long enough to extend around each of the adjacent sides. The outer label in the stack has been pasted throughout its whole extent, so that when the article is forced against this pasted label the label adheres to the article throughout the face in contact therewith. Thereafter when the article is forced between the wipers the ends of the label are pressed smoothly against the article, extending any desired distance around the sides of the same. It is of course manifest that the relative size of the articles and labels in the stack determines the extent to which the labels will extend around the sides of the article. It is of course understood that articles do not need to be of rectangular cross-section to be labeled in this machine, since articles of somewhat irregular shape may be operated upon.

The elevator D^7 is mounted to reciprocate vertically on the vertical rods D^{14} and is provided with the two guides D^5 , which may be laterally adjusted so as to properly engage articles of different size. The elevator is operated by the elevator-lever D^2 , connected to the elevator by the link D^3 . This lever is secured to the rock-shaft D^6 , to the outer end of which is secured the slotted link D' . The roll mounted on the crank D on the power-shaft D^4 engages this slotted link, which, as indicated, is formed with the relieved portions near the center of the same and by this means operates the elevator, as will be apparent. The relieved portions of the slot in this link serve to make a pause at either end of the movement of the elevator, so that the elevator is stationary at the top and bottom of its movement for a considerable time.

The plunger B , formed of any suitable material and preferably having a yielding face to engage articles properly, is adjustably secured to the plunger-slide B^7 by the set-nut indicated. The movement of this slide, which is mounted in suitable guides in the frame of

the machine, is effected by the link B' , which, as is indicated in Fig. 1, is pivoted to the member M , which is adjustably secured to the slide B^7 by the thumb-nut B^8 . The link B' is pivoted to the lever B^9 , (indicated in dotted lines in Fig. 1,) the lower end of this lever being connected by the link B^9 with the lever B^4 at the other end of the machine pivoted to the frame. The upper end of this lever is actuated by the cam B^6 on the power-shaft D^4 . If desired, of course, a suitable spring B^8 may be employed in this mechanism, which tends to hold the plunger downward and to maintain the lever B^4 in contact with the cam B^6 .

15 The ram G^{11} (indicated in Fig. 1) is formed with a face preferably of yielding material and adjustably secured to the ramrods G^9 , mounted to reciprocate in the frame of the machine. The rack G^8 is secured to these rods, 20 as indicated in Fig. 3, and the ram-sector G^7 , secured to the shaft G^6 , which is mounted in the bracket G^{12} , engages this rack and operates the ram. The counterweight G^{10} is secured to the shaft G^6 and serves to equalize 25 the movements of the parts. As seen in Fig. 2, the slotted link G^5 is secured to the shaft G^6 , and the upper end of the rod G^4 is adjustably secured in this slot, so that by this means the extent of movement of the ram may be 30 suitably varied. The lower end of the rod G^4 is connected with the bell-crank lever G^3 , (shown in dotted lines in Fig. 1,) this lever being connected by the link G^3 to the crank G . This crank is given an intermittent rotation 35 by the mutilated gear G^2 , which at each revolution engages the pinion G^{13} and rotates the crank through a complete revolution, so that by this means the ram is given a quick reciprocation, after which it is allowed to remain 40 in the position indicated in Fig. 1 for a considerable period.

The cushion H' , preferably of yielding material, is adjustably secured to the cushion-rods H^2 , mounted to reciprocate in suitable 45 bearings in the frame. The rack H^3 is also secured to and moves with the cushion-rods and is engaged by the pinion H^4 , as indicated in Fig. 1. This pinion is normally pressed forward by the spring H^5 , the force of which 50 may be suitably adjusted by the ratchet H^6 , secured to the spring and which is engaged by a suitable pawl H^{10} . The detent-wheel H^{15} , formed with the notches indicated, is engaged by the detent H^7 and operates to prevent the 55 return of the cushion and to hold the cushion in its outward position. The movement of the cushion is also regulated by the piston H^{14} , secured to the same, which operates in the air dash-pot H^9 .

60 The wipers H (indicated in Fig. 3) are pivotally mounted to move about the pins D^{14} , these wipers being preferably formed of yielding material and removably secured to the frames H^{17} . These wipers are held in the position indicated by the springs H^{12} , which en-

gage the frames and also a suitable stop H^{13} on the frame of the machine. The tail H^{11} of each of the frames is by this means held against a stop, so as to properly position the wipers.

70 The ejector-platform D^{10} is secured to the top of the frame of the machine and is formed with a suitable slot D^{13} . The ejector D^9 is mounted to move across this platform and is operated by a connection with the ejector-lever D^8 , which passes up through this slot. The ejector-lever, as is indicated in Fig. 3, is pivoted to the frame of the machine, and its outer end D^{11} is engaged by the ejector-fork D^{12} , which, as is shown in Fig. 1, is secured 80 to the rock-shaft D^6 . In this manner the ejector is reciprocated to force articles transversely along the ejector-platform, and, furthermore, when the ejector has reached the end of its stroke and has forced an article clear 85 of the cushion, the ejector moving into the position indicated in Fig. 3, the projection H^{16} on the ejector-lever engages the tail of the detent H^7 and releases this detent from the detent-wheel, so that the spring H^5 is allowed 90 to force the cushion forward into the position indicated in Fig. 3.

95 The operation of this machine is as follows, it being understood that a complete cycle of the machine takes place for every revolution of the power-shaft D^4 , which is rotated continuously by the pulley W : Articles are fed into the machine against the stop B^5 , and then the plunger B moves forward, carrying an article between the guides D^5 into contact with 100 the pasted outer label in the label-box. The elevator then moves upward, carrying the article and the adhering label with it, the grips E having been released to allow the label to be withdrawn from the label-box. 105 While the elevator is in this upward position, the paste-roll is tilted into a vertical position and then traversed across the label-box to apply paste to the outer label, the grips being under these conditions held against the 110 labels to retain them in the box. The paste-roll is then returned to its horizontal position in contact with the feed-roll. (Indicated in Fig. 1.) The pasted article is engaged by the 115 ram and moved into contact with the cushion. Then the cushion, article, and ram are moved together, so that the wipers engage the label and smoothly press the ends of the same down upon the two sides of the article. When the 120 article reaches its rearward position upon the ejector-platform, the detent H^7 comes into action and prevents the return of the cushion. The ram then retreats, leaving the article free. The ejector then operates to move the article 125 transversely along the ejector-platform out of the path of the cushion. The detent is then released, and the cushion is restored to its normal position. (Indicated in Fig. 3 by the spring.)

130 It is of course apparent that the labels in

the label-box may be of such a size as to extend around three sides of an article, or they may be of any other shape, so as to partially extend around the sides of the article, although 5 this machine is especially designed to apply labels to several sides of articles. It is manifest that many modifications may be made by those familiar with this art, and parts of this machine may be employed without using all 10 of the same and may be employed in connection with other devices without departing from the spirit of this invention. We do not, therefore, wish to be limited to the disclosure which we have made in this case; but 15

15 What we claim as new, and what we desire to secure by Letters Patent, is set forth in the appended claims:

1. In a labeling-machine, a label-box provided with movable grips to engage the outer 20 label in the box, a paste-roll mounted to tilt and to traverse across said label-box to apply paste to the outer label, an elevator, a plunger to force an article into said elevator and into contact with the pasted label in said label-box, means to operate said elevator to carry said article and the pasted label adhering thereto edgewise out of said label-box, movable wipers, a spring-pressed cushion, a ram to move said pasted article into contact 25 with said cushion and between said wipers to press the ends of said label upon said article and an ejector to move said article out of the path of said cushion.

2. In a labeling-machine, a label-box, means 30 to apply paste to the outer label in said label-box, a plunger to force an article into contact with said pasted label, an elevator to move said article and the pasted label adhering thereto edgewise out of said label-box and 35 means relatively movable with respect to said article to press the ends of said label upon said article.

3. In a labeling-machine, a label-box, means 40 to apply paste to the outer label in said box, a plunger to move an article into contact with said label, means to move said article and the label adhering thereto edgewise out of said label-box and means to press the ends of said label against said article.

4. In a labeling-machine, a label-box, means 45 to apply paste to a label in said label-box, means to press an article into contact with said pasted label and means to move said article to withdraw said label edgewise out of said label-box.

5. In a labeling-machine, a label-box, paste 50 apparatus and means to move an article into engagement with said label-box and to withdraw said article and the label adhering to said article edgewise from said label-box.

6. In a labeling-machine, a label-box, a paste 55 apparatus, means to press an article into contact with a pasted label in said label-box, means to withdraw said label and article from said label-box, wipers, a spring-pressed cushion

ion and a ram to press the ends of said label against said article.

7. In a labeling-machine, a label-box, a paste apparatus, means to move an article perpendicularly into contact with a pasted label in 70 said label-box, and means to press the ends of said label upon said article.

8. In a labeling-machine, a label-box, movable grips co-operating with said label-box, a paste apparatus comprising a feed-roll, a paste-roll, means to tilt said paste-roll and to traverse the same in contact with the labels in 75 said label-box to apply paste thereto, and a movable elevator operating adjacent said label-box to move an article and the label adhering 80 thereto away from said label-box.

9. In a labeling-machine, a label-box, a continuously-operating feed-roll mounted in a paste-reservoir, a tilting-shaft, traverse-rods secured to said tilting-shaft, a paste-slide 85 mounted to reciprocate upon said traverse-rods, a paste-roll mounted to rotate on said paste-slide and means to tilt said paste-roll out of contact with said feed-roll and to traverse said paste-roll adjacent said label-box 90 to apply paste to the labels therein.

10. In a labeling-machine, a label-box and paste apparatus comprising a paste-roll, means to tilt said paste-roll and to traverse the same 95 adjacent said label-box to apply paste to labels therein.

11. In a labeling-machine, a label-box, a movable elevator operating adjacent said label-box to remove an article from said label-box and paste apparatus operating to apply paste 100 to labels in said label-box while said elevator is away from said label-box.

12. In a labeling-machine, a cushion, a spring to operate said cushion, a detent to prevent the return of said cushion, wipers to engage an article, an ejector mounted adjacent said cushion, a ram, means to support an article having a label adhering thereto and means to operate said ram to force said article into engagement with said cushion and to 110 move it together with said cushion between said wipers to press the ends of said label upon said article, means to withdraw said ram and means to operate said ejector to move said article out of the path of said cushion, said 115 means disengaging said detent to allow the return of said cushion after said article has been removed from the path of said cushion.

13. In a labeling-machine, a spring-pressed cushion having a detent to prevent the return 120 of said cushion, a reciprocating ram, an ejector mounted adjacent said cushion, said ram operating to force a labeled article in contact with said cushion to press the label upon said article, said ram moving said article into the 125 path of said ejector, means to operate said ejector to move said article out of the path of said cushion and thereupon to disengage said detent to allow the return of said cushion.

14. In a labeling-machine, a spring-pressed 130

cushion to support an article, a detent to prevent the return of said cushion, means to move an article out of the path of said cushion and to disengage said detent to allow the return of said cushion after said article has been removed from the path of said cushion.

15. In a labeling-machine, a label-box, means to apply paste to labels in said label-box, a stop adjacent said label-box to aline articles with respect thereto and means to move an article perpendicularly into contact with a pasted label in said label-box.

16. In a labeling-machine, a label-box, means to apply paste to labels in said label-box, an elevator provided with laterally-adjustable guides, means to press an article between said guides into contact with a pasted label in said label-box and means to operate said elevator to move said article and the label adhering thereto away from said label-box.

17. In a labeling-machine, a label-box, to

support a stack of vertically-disposed labels, means to apply paste to said labels, a carrier having guides, means to press an article between said guides into contact with said labels 25 and means to operate said elevator to remove said article and the label adhering thereto away from said label-box.

18. In a labeling-machine, a label-box to support a stack of vertically-disposed labels, 30 means to apply paste to said labels, a vertically-movable elevator having a guide to aline articles with respect to said label-box, means to press an article into contact with said labels and means to operate said elevator to move 35 said article and the label adhering thereto vertically away from said label-box.

JAMES G. HENDRICKSON.
